DESIGN FOR A COMBINED COMB HOLDER AND WALL CABINET

Samuel Strick, New York, N. Y.

Application February 11, 1947, Serial No. 136,839

Term of patent 7 years

(Cl. D4—3)

To all whom it may concern:

Be it known that I, Samuel Strick, a citizen of the United States, residing at New York, in the county of Bronx, and State of New York, have invented a new, original, and ornamental Design for a Combined Comb Holder and Wall Cabinet, of which the following is a specification, reference being had to the accompanying drawing, forming part thereof.

I claim:

The ornamental design for a combined comb holder and wall cabinet, as shown.

SAMUEL STRICK.
